CLAIM

The ornamental design for a bar table unit, as shown and described.

DESCRIPTION

FIG. 1 is a front elevational view of a bar table unit showing my new design with the pedestal door closed;

FIG. 2 is a front elevational view thereof with the pedestal door open;

FIG. 3 is a front elevational view thereof with the pedestal door open. Remote controls, drink openers, plates and serviette dispenser added.

FIG. 4 is a top plan view thereof with the edible container covered with its lid;

FIG. 5 is top plan view thereof with the edible container open. Stone like ornaments added;

FIG. 6 is an isometric view from one side with the pedestal door closed, edible container covered with its lid and ornaments added;

FIG. 7 is an isometric view from one side with the pedestal door open and edible container open;

FIG. 8 is an isometric view from one side with the plates and serviette dispenser added. Also added are the ornaments;

FIG. 9 is a rear elevational view thereof; and,

FIG. 10 is a right side elevational view thereof.

The remote controls, drink openers, plates and serviette dispenser in the bar table unit are shown in broken lines for illustrative purposes only and form no part of the claimed design
